(57) **CLAIM**

We claim the ornamental design for a handheld inflatable underwater viewing window, as shown and described.

DESCRIPTION

FIG. 1 is perspective view of a handheld inflatable underwater viewing window according to the present invention; FIG. 2 is a top view of the viewing window; FIG. 3 is a front view of the viewing window; FIG. 4 is a rear view of the viewing window; FIG. 5 is a bottom of the viewing window; FIG. 6 is a right-side view of the viewing window; and, FIG. 7 is a left-side view of the viewing window. The broken line in the figure drawings represents unclaimed portion of the design and forms no part of the claim.

1 Claim, 5 Drawing Sheets
